DISGUISE

William A. Hall, Los Angeles, Calif., assignor to
Max Factor & Co., Los Angeles, Calif., a corpora-
tion of Delaware

Application May 31, 1932, Serial No. 614,455

8 Claims. (Cl. 2—206)

This invention relates to a method of and means for producing artificial semblances, or disguises. By the aid of this invention, any body portion can be arranged to take on either a usual or grotesque or abnormal appearance, either animal or human. This appearance is not only obtained for quiescent or immobile purposes; since with the aid of the invention, motions or actions of the disguised body portion cause equivalent 5 and quite natural motions of the overlying disguising material.

The body portion so disguised or altered in appearance, can for example, be an arm or a leg, the trunk, or head, or any parts thereof. 10 Thus an arm and hand can be overlaid with the disguise, and the bending of the arm at the elbow will not be interfered with, but on the contrary, the artificially created disguise will appear to move quite in accordance with the assumption 15 that it represents living parts. Such artificial effects have been heretofore difficult in connection with the face and head especially. Such acts as talking, smiling, winking, etc., have been, before this invention, substantially impossible to 20 reproduce in such manner that these acts appear "natural" to the disguised parts. For example, the simple act of opening and closing the mouth is impossible of reproduction through a usual mask, except by the very apparent and crude 25 expedient of hinging the jaw part of the mask to the main part thereof. An expedient of this sort can of course deceive no one.

On the contrary, by the aid of this invention, an actor can be caused to take on the guise of 30 a natural or particular person, of different appearance; and the disguise will appear to act entirely naturally. This makes it possible to produce unusual or abnormal effects either on the stage or for motion pictures, the finished creation being to all intents and purposes, capable 35 of exhibition as an entirely "natural" (that is, non-artificial) being. All muscular actions such as talking, laughing, walking, etc., can be indulged in without danger of anyone penetrating 40 the disguise. Of course, where the make-up effect is purposely grotesque, macabre or fanciful, it is tentatively and in a matter-of-fact way 45 recognized as an artificial creation solely because of the character of the creation, and not because of any serious flaw in the "natural" or 50 non-artificial actions of the creation.

It is possible to create these effects by providing 55 an overlying cover upon the body portion the appearance of which is to be changed, the cover being in accurate register with the over-

laid parts, and of flexible nature to conform readily to muscular actions. For example, if the head is to be overlaid, an integral head covering closely fitting the head of the wearer, is used; and the outer contour is made to conform 5 to the desired appearance. The shape of the head so created as well as the features of the disguise can be totally different from those of the wearer.

It is therefore one of the objects of this invention to make it possible to alter the appearance 10 of a body member, such as the head and features, while yet retaining a "natural" or non-artificial appearance.

It is another object of this invention to provide 15 a method of procedure whereby the desired simulations are accurately fitted to the wearer.

This invention possesses many other advantages, and has other objects which may be made 20 more easily apparent from a consideration of several embodiments of the invention. For this purpose there is shown a few forms in the drawings accompanying and forming part of the present specification. These forms shall now be described in detail, which illustrate the general 25 principles of the invention; but it is to be understood that this detailed description is not to be taken in a limiting sense, since the scope of the invention is best defined by the appended claims.

Referring to the drawings:

30

Figure 1 is a perspective or pictorial view of a disguise to be used on the head and neck of a wearer;

Fig. 2 is a sectional view of a part of the apparatus in use for producing the creation; 35

Fig. 3 is a fragmentary perspective view of another part of the apparatus;

Figs. 4, 5 and 6 are detail sections, for elucidating one of the steps in the process of producing 40 the disguise;

Fig. 7 is a diagrammatic section of a face with the disguise in place;

Figure 8 is a detail section of the eye portion of the disguise; and

Fig. 9 is a diagram of an arm and its disguise, 45 incorporating the invention.

The following description will be made for a disguise to be used by a living wearer, as this presents more difficult problems; but of course 50 the disguise can be utilized for inanimate as well as animate wearers. Furthermore, the disguise can be used on forms corresponding not only to the head or neck portions, but to any other portions of the body, or as a complete covering for 55

the body. The disguise may be grotesque or beautiful, as determined by the requirements.

In order to make such a disguise appear natural, the muscular actions of the wearer must be permitted by the disguise in a natural way. This is accomplished by proper considerations to the anatomy of the part disguised. For example, if the head is to be overlaid with the disguise, the movements of the mouth in speaking, should be not only left unhindered, but the disguise should simulate these movements without the necessity of forming severed parts for the mask portions. Perhaps the most difficult element in this connection is in relation to the buccal or cheek muscles, and the lip muscles, which are capable of a wide variety of muscular actions, such as to laugh, smile, and in general, to express a wide variety of emotions. The muscles neighboring the eye are also of the same general character.

It has been found that this naturalness can be readily attained by an integral, unsevered member that yields without material resistance to the muscular acts and that nevertheless returns to conditions of repose when the muscles are returned to repose. It is apparent that if a mere mask or covering of solid material be used, closely conforming and covering the part to be disguised, and of varying thickness of material to comply with the desired semblance, a great resistance is imposed on the free muscular actions, which would prevent material muscular action and so alter such action as to make it appear unnatural.

In order to solve this problem, use is made, in one form of this invention, of a pair of layers, in the form of integral inner and outer membranes. The inner layer or membrane is very thin and resilient or elastic, and closely contacts with the part to be disguised. It therefore offers no appreciable resistance to the muscular actions. The outer layer is formed from readily yielding material which can bend or give to conform to the muscular action, but without offering resistance thereto. At those places where there is least or no muscular action (as at the cheek bones, the upper part of the forehead, and the bridge of the nose), the layers can be integrally attached. At these points also, the disguise can be fastened, as by an adhesive, to the wearer. The voids between the two layers can, if desired, be filled with plastic material, such as cotton batting, or a liquid, or air; or they can be left unfilled, the thickness of the outer layer being built up sufficiently between these points of attachment to be substantially self-supporting, yet yielding to conform to the movements of the inner layer.

As an example of such a device, Fig. 1 shows a head and neck disguise, exaggerated or abnormal in appearance in order to bring out these points in a clear and distinct manner. It is here seen that the nose, lips, chin and the dome of the head are enlarged and made to have unusual shapes. However, in most instances, such disguises conform more closely to the configuration of the wearer. At the edges of the natural openings, such as the eyes, lips, ears and nostrils, the disguise covering must be thinned down to provide naturalness; but elsewhere there is no prohibition on the extent to which the outer membrane can depart from the inner membrane to build up the disguise.

The step of forming the inner, closely contacting layer will now be described. An exact replica of the wearer is first made, as by a plaster cast.

This replica is made when the wearer is in an up-

right position, the lips being slightly parted, and the eyes closed, but otherwise relaxed. The slight parting of the lips is advantageous to provide a medial or average condition of the contacting layer. Such a replica is shown at 1 in Fig. 2. The process of plaster casting is probably the most satisfactory way to secure this replica, care being taken to fashion the ears, lips, nose, and eye regions in exactitude with the wearer. For this purpose supplemental measurements can be made to obtain exact head contours at the back, the exact shape of the eye regions below the brows, and the exact shape of the ears and lips. Preferably the mouth cavity 2 is extended through the neck 3, and the entire replica can be mounted for convenient handling, on a spindle or support 4, embedded or cast therein.

The replica 1 is then covered with some material (such as soapy water) that will not adhere to rubber composition. This composition is then sprayed over the replica 1. Alternatively, the replica 1 can be dipped in the solution. This first layer is of the order of .0015 to .002 inches thick. Succeeding dippings or sprayings can be made to build up the layer 5 to the desired thickness, which may be of the order of one sixty-fourth of an inch. This composition is elastic and thin enough so that it will stretch readily and return to normal position in simulation of the muscular actions of the wearer.

In some places, such as adjacent the natural openings (eyes, lips, nostrils), or adjacent the points of little muscular action, as at the bridge of the nose, cheek bones, a few points of the forehead, the elastic membrane 5 should shade off to single thickness. To accomplish this conveniently, after the first layer is made, a spot of soap or other non-adherent can be painted or marked on the surface that is to stay thin. The succeeding layer will not adhere to this spot; and the edges of the thin spot can be gradually thickened as by subsequent painting of overlying or overlapping spots. Then after completion, the unadhered layers can be removed, by carefully cutting them at the edges of the thinned spots. The area of the first spot of soapy layer if made, for example, for the purpose of defining an orifice for the eye, is made in conformity with the eye opening, so that the edge of the orifice just defines the outer edges of the eyelids; and when this edge is attached, the exterior surfaces of the wearer's eyelids will be exposed and form a natural appearing continuation of the disguise. The same is true of the edges of the lip, ear, and nostril defining openings. The lip portion is provided with reentrant parts to overlie the lips of the wearer completely. This reentrant portion enters between the lips and the teeth.

By appropriate variations of the forms of the non-adherent spots on successive layers, the edges defined after cutting away the unattached layers can be either abrupt or square or tapering inwardly or outwardly.

In other spots or localities of this elastic layer, similar reductions in thickness are desirable without actually removing all of the rubber. For example, this may occur at the cheek-bones, at the bridge of the nose, at the edge of the lower jaw, or at the forehead.

After sufficient thickness of the elastic layer is thus obtained, it can readily be pulled off of the replica 1, and the unnecessary thicknesses cut away, as just described.

There will now be described the process of form-

ing the outer yielding layer that carries the semblance of the disguise.

The first step is to model over the replica 1 or a duplicate thereof, as with clay, the features of the disguise. The completed device is then a replica of the wearer's appearance, and will look in general like the head of Fig. 1. From this completed replica, a female mold 8 is made, the face portion being shown in Fig. 3. This mold 10 is then covered with soap to keep the rubber composition from adhering to it. Then the mold surfaces are sprayed or dipped with the composition, providing the layer 9 (Fig. 4). Repeated dippings or sprayings, such as shown in Fig. 5, 15 build up this layer. As before, spots like 10 of non-adhering material can be painted on successive layers to control the building up of the composition at these points. The bridge of the nose and the nostril areas are shown as thus treated. 20 The thickness of all layers are shown greatly exaggerated.

The completed outer membrane 11 (Fig. 7) can be much heavier than the elastic membrane 5. The deeper cavities inside member 11 can be partially filled with the plastic material, such as in 25 the chin or nose. The final thicknesses are somewhat as shown in Fig. 6. After membrane 11 has been built up, it can be removed from mold 8, and the natural apertures cut out. This then forms 30 a supplemental yielding layer having the semblance of the desired disguise. It can then be cut and fitted around the inner layer 5, and attached to it in spots such as the area covering the cheek bones, the forehead, the edges of the lips, 35 nostrils, and eye openings, or other places corresponding to little muscular action. After this is done, the cut part can be reunited as by sewing or dipping or painting with plastic composition. Then the larger voids, such as 12 (Fig. 7) can be 40 filled as by batting, liquid, or the like to render the parts self-supporting.

In some instances the outer membrane 11 can be omitted, especially where the disguise is not intended materially to alter the shape of the disguised member, but only to change its appearance, such as to make the wearer appear younger or older. Under such circumstances, the membrane is made thin enough to transmit muscular motion. Such masks or disguises can be most 50 conveniently formed as a covering for the face only, when the wearer is a woman having sufficient hair to hide all other naturally exposed parts of the head.

In Fig. 7, the disguise is shown as it would be 55 disposed on the wearer. The thin resilient layer 5 is preferably attached to the head at points where there is little muscular action, whereby the disguise is simulative of muscles, being free and anchored in substantial exactness with the 60 muscles that are moved by the wearer. Thus the bridge of the nose, the cheek bones, the lower edge of the lower jaws, etc. can serve as anchoring places. A detail of the eye opening is illustrated in Fig. 8, showing how the edges of the 65 disguise are joined to the brows and to the lower line of the lower lids. The disguise can extend down as far as the shoulders, where the inner and outer membranes can be integrally joined.

Prior to the combining of both layers 5 and 11, 70 these layers can be vulcanized to any desired extent.

In Fig. 9, a hand is shown as disguised to form 75 an animal arm or hand by the same form of device as used for the head. In this case, the

anchoring spots would be the knuckles and joints of the hand and arm.

The finishing off of the disguise will now be described. After the two layers are united, there may be a complete layer of transparent or opaque 5 rubber on the disguise. A background flesh color is obtained by mixing into this coating, powder color which almost but not quite dissolves therein, leaving a textured appearance. The powder color should be vegetable or other material that 10 is inert chemically as regards the rubber composition.

After this background color is obtained, pastels can be applied and rubbed in without a binder, 15 by hand, to provide the final color appearance. Then the disguise is again dipped in transparent compound to provide a sealing and protecting layer, effectively preventing loss of any color.

The skin texture can be obtained by appropriate treating of the replica (Fig. 1) from which 20 the mold 8 is made, as by brushing, or rubbing with a sponge rubber or the like. Hair can be applied by appropriate adhesives, as desired, on the head, chin, lips or brows; or else appropriate wigs or toupees can be used for this purpose. 25

I claim:

1. A disguise for a muscularly actuated part of a wearer comprising a thin resilient layer for closely contacting with the part of the wearer to be disguised, and a supplemental yielding 30 layer joined to the resilient layer at places corresponding to little or no muscular movement.

2. A disguise comprising a thin resilient layer for closely contacting with the part of the wearer to be disguised, and a supplemental yielding layer 35 capable of yielding in accordance with muscular actions of the disguised part without appreciable resistance, joined to the resilient layer at places corresponding to little or no muscular movement. 40

3. A disguise for a muscularly actuated part of a wearer comprising an integral member having a surface closely contacting with the wearer, and joined to the wearer where there is little or no muscular action, said member being in two 45 layers, one for forming said contact, and the other for providing the altered appearance.

4. A disguise for a muscularly actuated part of a wearer comprising an integral member having a surface closely contacting with the wearer, and joined to the wearer where there is little or no muscular action, said member being in two 50 layers, one for forming said contact, and the other for providing the altered appearance, said two layers being joined at the places where there is 55 little or no muscular action.

5. A disguise for the head portion, comprising a thin resilient layer completely overlying and contacting with the head portion, and a supplemental layer, said supplemental layer being connected to the resilient layer only at places where there is little or no muscular action. 60

6. A disguise adapted to be worn over the face of the wearer, comprising a thin closely contacting elastic layer, said layer having openings corresponding to the natural openings of the face, the material of the layer adjacent the openings gradually decreasing in thickness as the edges of the openings are approached. 65

7. A disguise adapted to be worn over the face of the wearer, comprising a thin closely contacting elastic layer, said layer having openings corresponding to the natural openings of the face, and a supplemental layer fastened to the 75

contacting layer adjacent the openings thereof, gradually decreasing in thickness as the edges of the openings are approached, and a supplemental layer fastened to the contacting layer adjacent the openings thereof, and having parts unattached to the thin layer.

8. A disguise adapted to be worn over the face of the wearer, comprising a thin closely contacting elastic layer, said layer having openings corresponding to the natural openings of the face, the material of the layer adjacent the openings

gradually decreasing in thickness as the edges of the openings are approached, and a supplemental layer fastened to the contacting layer adjacent the openings thereof, and having parts unattached to the thin layer.

WILLIAM A. HALL
